(57) **CLAIM**

The ornamental design for a juicer as shown and described.

DESCRIPTION

FIG. 1 is a first perspective view of a juicer, showing my new design, in a first configuration;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of thereof, shown in a second configuration.
The broken lines in the drawings depict portions of the juicer that form no part of the claimed design.

1 Claim, 9 Drawing Sheets
